Specification for Design.

Patented Nov. 4, 1919.

Application filed July 14, 1919. Serial No. 310,865. Term of patent 14 years.

To all whom it may concern:

Be it known that I, **ALFRED C. GILBERT**, a citizen of the United States, residing in New Haven, New Haven county, Connecticut, have invented a new, original, and ornamental Design for a Toy Express-Wagon, of which the following is a specification, when taken in connection with the accompanying drawing.

The drawing shows a perspective view of a toy express wagon embodying my new design.

What I claim is:

The ornamental design for a toy express wagon, substantially as shown.

ALFRED C. GILBERT.
